INDEXING DEVICE

Hermann Hill, Syracuse, N. Y., assignor to Easy
Washing Machine Corporation, Syracuse, N. Y.,
a corporation of Delaware

Application July 13, 1931, Serial No. 550,507

20 Claims. (Cl. 259—144)

This invention relates to a new and improved indexing device.

My invention is particularly well adapted for use with washing machines of the so-called vacuum cup type in which the vacuum cups are carried on a reciprocating piston and are intermittently partially moved circumferentially of the vat so that when they are carried downwardly by the piston, they will contact with different parts

10. of the batch of clothes.

The main object of my invention is to provide an indexing device which will cause the partial rotation of a reciprocating piston in one direction, and a subsequent partial rotation of the piston in the opposite direction.

Another object is to provide an indexing device which will not affect any rotary movement of the piston during the major portion of its upward movement, but will affect such movement as the piston approaches the end of its upward travel so that the vacuum cups may be lifted directly upward from the clothes and will not be carried circumferentially of the vat until they have passed above the water level.

25. Another object is to provide an indexing device which will not cause any rotary movement of the piston during its downward movement so that the vacuum cups will be carried directly downwardly into contact with the clothes.

30. Another object is to provide an indexing device which is particularly well adapted for use in a washing machine of the vacuum cup type in that it insures that all of the clothes in the washing vat, irrespective of their location therein, will be subjected to the action of the vacuum cups.

Other objects and advantages relate to the size, shape and arrangement of parts all as will more fully appear from the following description taken 40 in connection with the accompanying drawings in which:—

Figures 1, 2, 3 and 5 are elevations of my indexing device in different positions of its movement.

45. Figure 4 is a top plan view of the vacuum cups of a washing machine indicating in full and in dotted lines, the different positions assumed by the cups during the operation of the indexing device.

50. Figure 6 is a diagrammatic view indicating the path of movement taken by the piston due to the action of the indexing device.

Figure 7 is an elevation, partially broken away and partially in section, of a washing machine embodying my invention.

Figure 8 is a section on line 8—8 of Figure 7.

Figure 9 is a section on line 9—9 of Figure 8.

Figure 10 is a section on line 10—10 of Figure 7.

Figure 11 is a section on line 11—11 of Figure 10.

Figure 12 is a section on line 12—12 of Figure 7.

Although my invention may be used in combination with various devices, I have here shown it as used in a washing machine of the vacuum cup type comprising a main frame 1 having the usual supporting legs 2, and having supported thereon a washer vat 3.

On the under surface of frame 1 is secured a 15 depending gear casing 4 inclosing a set of reducing gears not shown which are operatively connected to an electric motor not shown.

Referring to Figures 7 to 12, a drive shaft 5 extends outwardly from gear casing 4, and has 20 secured thereto, a crank 6.

In the end of crank 6 is secured a laterally extending crank pin extension 7 upon which is rockingly positioned a connecting rod 8. Connecting rod 8 is secured in position on crank pin extension 25 7 by means of a washer 9 and a split ring 10.

On the outer end of crank pin extension 7, and in this case shown as formed integral therewith, is a spur pinion 11.

30. A main arm 12 is pivotally mounted in the forked end 13 of connecting rod 8 as by a pivot pin 14. One end of main arm 12 is pivotally mounted on a pivoting link 15 which, in turn, is pivotally mounted on main frame 1, intermediate the end of main arm 12 which is mounted on pivoting link 15, and the pivotal point of main arm 12 on connecting rod 8, such main arm 12 is pivotally mounted on a compensating crank 16 which is pivotally mounted on gear casing 4 as by a pivot pin 17.

35. A vertically extending tubular supporting post 18 is secured in vat 3 at approximately the central point thereof and extends upwardly to a point above the normal level of the washing fluid which is in the vat during use.

40. A piston 19 is slidably mounted in post 18 with one end extending above the upper end of post 18 and with its lower end extending downwardly beneath frame 1.

45. On the upper end of piston 19 are secured a plurality, in this case shown as three, of spaced depending vacuum cups 20.

50. Adjacent the lower end of piston 19 is secured as by a pin 21, an annular collar 22. Beneath collar 22 and rotatably mounted on piston 19 is 55

a bevel gear 23, a friction disk 24 being interposed between collar 22 and gear 23.

Beneath gear 23 is positioned on piston 19 a pivoted trunnion 25 having laterally extending 5 trunnions 26 and 27.

Pivoted trunnion 25 and gear 23 are held in position on piston 19 by means of a washer 28 and a nut 29, which nut 29 is securely held against displacement as by a pin 30.

10 One end of main arm 12 is forked, as shown in Figure 11, and is rockingly mounted on trunnions 26 and 27.

It will be evident that when the device is operating, crank 6 will be rotated to carry connecting 15 rod 8 upwardly and downwardly, and this in turn, will cause piston 19 to be reciprocated in post 18 to raise and lower the vacuum cups 20.

20 One end of main arm 12 being pivoted on the pivoting or swinging link 15, the reciprocating movement of piston 19 is permitted to take place in a straight line so that there may be no possibility of piston 19 binding in post 18.

25 For the purpose of assisting in the upward movement of main arm 12, I provide a spring 31 having one end secured to main frame 1 and having the other end secured to main arm 12 inside its pivot on link 15.

30 My indexing device comprises a spur gear 32, which is rotatably mounted on a stub shaft 33 secured in connecting rod 8.

35 On stub shaft 33 and abutting against spur gear 32 is a cam member 34 secured against relative movement in relation to spur gear 32 as by pins 35. Cam 34 and spur gear 33 are held in position on stub shaft 33 as by a washer 36, and a cotter pin 37.

40 Spur gear 32 is in mesh with spur pinion 11 so that when crank 6 is rotated, spur gear 32 carrying cam 34 will be rotated on stub shaft 33. Although the ratio between spur pinion 11 and spur gear 32 may be varied as desired, I have here shown the same as being in the ratio of four to one.

45 Beneath stub shaft 33, there is secured in connecting rod 8, a second stub shaft 38.

50 A bell crank 39 is rockingly mounted on stub shaft 38 and is held in position thereon, as by a washer 40 and a cotter pin 41.

55 One arm of bell crank 39 carries a roller follower 42 which is in contact with cam 34, such contact being maintained by means of a spiral spring 43 which has one end secured to the other arm of bell crank 39, and its other end secured to pivoting link 15.

60 The second arm of bell crank 39 is secured as by a link 44 to the lower end of a bevel gear segment arm 45.

65 Bevel gear segment arm 45 is pivotally mounted on trunnion 21 and carries on its upper end a bevel gear segment 46 in mesh with bevel gear 23.

70 As spur gear 32 is rotated, the roller follower 42 on the bell crank 39 will follow the cam faces on cam 34 to rock bell crank 39 about its pivot 38. This, in turn, will cause the lower end of bell crank 39 to be moved towards and from the piston 19, and this movement through link 44, will cause bevel gear segment arm 45 to be rocked about its pivot to cause bevel gear segment 46 to move bevel gear 23, and this movement of bevel gear 23 will, through friction disk 24 and annular collar 22, cause a partial rotary movement of piston 19, which will carry with it vacuum cups 20. Friction disk 24 is provided so that in case clothes 75 are entangled with the cups 20, spur gear 23 may

slip on disk 24 so that its movement will not be communicated to piston 19.

Operation

In manipulating the cups of a washer of the 5 vacuum cup type, it is desirable that when the cups are raised in the vat, they move in a straight line until they have emerged from the washing fluid, and immediately thereafter, they be moved a short distance circumferentially of the vat as 10 their upward movement is completed. It is then desirable that they be moved downwardly in a straight line to the limit of the downward movement.

To explain how my indexing device accomplishes the purpose for which it is designed, I have indicated on Figures 1, 2 and 3, the position of the parts at different stages of the indexing movement.

For the purpose of this explanation, it may be 20 assumed that the parts are in the position shown in heavy lines shown on Figure 1, when the cycle of movement is initiated. In this position, the crank 6 is in the lowermost position, as is the connecting rod 8, and the main arm 12.

25 The bevel gear segment 46 is at its extreme limit of movement which it may take in moving the piston 19 in counter-clockwise direction.

30 The roller follower 42 is in contact with one end of the cam face *a* on cam 34. As the crank 6 30 is rotated in a clock-wise direction, the connecting rod 8 carrying the main arm 12, and the indexing assembly will be raised upwardly, and during this movement, the cam 34 will be moved in a counter-clockwise direction.

35 The cam face *a* is of such a shape that as the parts are raised to the position shown in dotted lines on Figure 1 in which position the vacuum cups 20 will have been raised above the liquid in the washing vat, the cam face *a* will not have 40 effected any movement of the bell crank 39 so that the bevel gear segment 46 will have remained at rest in relation to the bevel gear 23. As the crank 6 continues to carry the parts upwardly, the roller follower 42 will have moved 45 on the cam face *a* from the position shown in dotted lines on Figure 1 to the position shown in heavy lines on Figure 2, and during this movement, the cam face *a* will have caused the bell crank 39 to move about its pivot to rock the bevel 50 gear segment arm 45, and this movement will, through bevel segment gear 46 and bevel gear 23, cause a partial rotation of piston 19 in a clock-wise direction to carry the cups 20 approximately 30 degrees circumferentially of the vat 3. 55

This movement will bring the parts into the position shown in heavy lines on Figure 2, and in this position, the crank 6 will have completed one-half a revolution and will have carried the parts to the limit of their upward movement. As the crank 6 continues its rotation to carry the parts downwardly from the position shown in heavy lines on Figure 2 to the position shown in dotted lines on Figure 2, the roller follower 42 will pass from the cam face *a* of cam 34 on to one 60 end of the adjacent cam face *b*, as shown in dotted lines on Figure 2.

65 Cam faces *a* and *b* are so designed that this movement of roller follower 42 will not move bell crank 39 about its pivot, and in consequence, the bevel segment gear 46 will remain in fixed relation to the bevel gear 23 so that no rotation of piston 19 will take effect during the movement of the parts from the top to the bottom position.

70 As the crank 6 begins its second rotation, the 75

parts will be carried from the position shown in dotted lines on Figure 2 to the position shown in heavy lines on Figure 3, in which latter position, the vacuum cups 20 will have been raised above the level of the liquid in vat 3.

During this movement of parts, the roller follower 42 will have moved a short distance on cam face b, but the relation of parts is such that such movement of roller follower 42 on cam face 10 b will cause no movement of bell crank 39 about its pivot so that bevel gear segment 46 will remain in fixed relation to bevel gear 23.

As crank 6 continues its upward movement to carry the parts from the position shown in 15 heavy lines on Figure 3 to the position shown in dotted lines on Figure 3, cam face b will bear against roller follower 42 to move bell crank 39 about its pivot which, in turn, will rock bevel gear segment arm 45, and this in turn, through 20 bevel gear segment 46 and bevel gear 23, will cause the rotation of piston 19 to carry the cups 20 a further 30 degrees circumferentially of vat 3, and when the crank 6 has completed the half 25 revolution to carry the parts to their uppermost position, they will be in the relation shown in dotted lines on Figure 3 with bevel gear segment 46 in its farthest limit of movement in moving piston 19 clockwise.

The continued rotation of piston 6 will cause 30 the parts here described to be carried downwardly to the bottom position, and during this movement roller follower 42 will have moved from cam face b to the beginning of cam face c and into the position shown in heavy lines on Figure 5.

35 The relation of parts is such that as roller follower 42 moves from cam face b to cam face c, the bell crank 39 will not be moved about its pivot so that bevel gear segment 46 will remain in fixed relation to bevel gear 23. After this movement has been effected, the continued rotation of crank 6 will cause the parts to be carried 40 upwardly into the position shown in heavy lines on Figure 5, and the cups 20 raised above the level of the liquid in vat 3.

45 The relation of parts is such that during this initial upward movement, the roller 42 will move on cam face c without effecting any movement of bell crank 39 about its pivot so that bevel gear segment 46 will remain in fixed relation to bevel gear 23.

During the continued upward movement of crank 6 to carry the parts from the position shown in heavy lines on Figure 5 to the position shown in dotted lines on such figure, the roller 50 follower 42 will follow the concave face of cam face c to permit the bell crank 39 to be moved about its pivot in a direction opposite to that in which it was moved when in contact with cam faces a and b so that the bevel gear segment 55 arm 45 will be rocked in an opposite direction, and this through bevel gear segment 46 and bevel gear 23, will cause piston 19 to be partially rotated in a counter-clockwise direction to carry the cups 20, 30 degrees circumferentially of the vat 3.

60 Although I have not here shown the further relation of parts on the drawings, it will be understood that as crank 6 continues its rotation to carry the parts to the bottom position, the roller follower 42 will move from the cam face 65 c to the cam face d with no affect on the rotary movement of piston 19 during its downward movement or during the next succeeding initial upward movement.

The continued movement of roller follower 42 70 along cam face d after the cups 20 have emerged

from the washing fluid in the vat 3 will permit the movement of bell crank 39 about its pivot to carry bevel gear segment 46 from the position shown in dotted lines on Figure 5 to the position shown in heavy lines on Figure 1 to effect a second rotary movement of piston 19 to carry cups 20 a further 30 degrees circumferentially of vat 3.

After this last movement of bevel gear segment 46, the parts will be returned to the bottom position without affecting the relation of bevel gear segment 46 to gear 23, and when they are in this bottom position, one cycle of movement will have been completed, and a further operation of the device will again carry the parts through a similar cycle of movement.

When the piston 19 is characterized in the specification and claims as being partially rotated, the expression means that the piston as a unit is rotated less than a full revolution.

Figure 4 is a top plan of the vacuum cups 20 showing the different positions taken by them during the cycle of movement just described.

Figure 6 indicates the path of movement taken by the cups during the cycle just described. Starting at the left of this figure, the path of movement of the cups during the first half of the cycle is indicated by heavy arrows, and the return movement during the second half of the cycle is indicated by dotted arrows.

I have here shown a cycle of movement in 30 which the cups are carried 30 degrees circumferentially of the vat twice and are then carried 30 degrees circumferentially of the vat in the reverse direction, by two movements to bring them back to the starting point. It will be understood, however, that the number of consecutive movements in each direction may be varied if desired, and it will also be understood that the point in the upward movement of the piston at which the rotary movement of the same begins 35 may also be changed, if desired, for although I have shown and described a specific structure and form and relation of parts as an exemplification of an embodiment of my invention, I do not desire to restrict myself to the exact size, shape 40 or relation of parts as various changes may be 45 made within the scope of the appended claims.

I claim:

1. In an indexing device, a piston, means for moving the piston upwardly, means operative at a given point in the upward travel of the piston for partially rotating the same by friction in one direction, means for moving the piston downwardly with the rotating means inoperative, and means operative at a given point in a second upward movement of the piston for partially rotating the same by friction in the opposite direction.

2. In an indexing device, a piston, means for reciprocating the piston vertically, means for partially rotating the piston by friction in one direction during an upward movement thereof, and means for partially rotating the piston in the opposite direction by friction during a subsequent upward movement thereof.

3. In an indexing device, a piston, means for reciprocating the piston vertically, means for partially rotating the piston by friction in one direction during an upward movement thereof, and means for partially rotating the piston in the opposite direction by friction during a subsequent upward movement thereof, said rotating means being ineffective during the downward movement of the piston.

4. In an indexing device, a piston, means for

an upward movement thereof and then in the opposite direction upon a subsequent upward movement thereof.

16. In an indexing device for clothes washing machines, a plunger, means for reciprocating said plunger, a non-positive connection, means for rotating said plunger through said non-positive connection first in one direction upon an upward movement thereof and then in an opposite direction upon a subsequent upward movement thereof, and means for causing said rotational movement to occur after said plunger has started its upward movement.

17. In an indexing device for clothes washing machines, a plunger, means for reciprocating said plunger, a non-positive connection, means for rotating said plunger through said non-positive connection first in one direction upon an upward movement thereof and then in an opposite direction upon a subsequent upward movement thereof, and means comprising a cam for causing said rotational movement to occur after said plunger has started its upward movement.

18. In an indexing device for washing machines wherein washing elements are reciprocated in a vat, a vertically reciprocable rod adapted to actuate said washing elements, means for reciprocating said rod, and means for rotating said rod including a friction connection operable at a

point in the upward travel of said rod near the top of its stroke, said friction connection being adapted to prevent rotation of said rod during the downward travel thereof.

19. In an indexing device for washing machines wherein washing elements are reciprocated in a vat, a vertically reciprocable rod adapted to actuate said washing elements, means for reciprocating said rod, a cam adapted to be rotated by said rod reciprocating means, means actuated by said cam for rotating said rod including a friction connection operable at a point in the upward travel of said rod near the top of its stroke, said cam and friction connection being adapted to prevent rotation of said rod during the downward travel thereof.

20. In a washing machine, a vat, washing elements in said vat, a vertically reciprocable rod for actuating said washing elements, means for reciprocating said rod, said means being adapted to raise said washing elements above the normal fluid level of said vat, and means for rotating said rod including a friction connection operable at a point in the upward travel of said rod when said washing elements are above the normal fluid level of said vat, said friction connection being adapted to prevent rotation of said rod during the downward travel thereof.

HERMANN HILL.
